UNITED STATES PATENT OFFICE

ARTHUR W. REYNOLDS, OF LEONARDSVILLE, NEW YORK, ASSIGNOR TO THE BABCOCK MANUFACTURING COMPANY, OF LEONARDSVILLE, NEW YORK, A CORPORATION OF NEW YORK

CULTIVATOR

Application filed May 9, 1927. Serial No. 189,848.

This invention relates to new and useful improvements in cultivators and has for its object the general improvement, including the simplification, of the adjustable slide movable longitudinally of the center or main beam of the cultivator for effecting lateral adjustments of the side beams thereof.

An additional object is to provide an adjustable slide formed from a single piece of sheet metal suitably punched and folded.

A further object is to provide a one piece adjustable slide and a simplified and novel connection between the same and an operating lever.

Other and additional objects will appear from a consideration of the following detailed description taken in connection with the accompanying drawing wherein there is shown a satisfactory embodiment of the invention. It is to be understood that this description and drawing are by way of illustration only and that reference must be had to the appended claims for a definition of the limitations of the invention.

In said drawings:—

Fig. 1 is a perspective view of a cultivator having the invention applied thereto, parts being broken away to show more clearly the application of the invention;

Fig. 2 is an elevation showing a fragment of the cultivator with the adjustable slide in place thereon and showing the position of the connecting link during rearward movement of the slide;

Fig. 3 is a view similar to Fig. 2, but showing the relation of parts during the forward movement of the slide;

Fig. 4 is a plan view of the parts shown in Fig. 2;

Fig. 5 is a perspective view of the adjustable slide alone, and

Fig. 6 is a detail showing a part of the operating lever.

Referring in detail to the drawing, the cultivator includes a center beam 10, provided at its forward end with a hook or the like 11 to which a suitable draft means may be connected. Secured to the main or center beam 10 adjacent its forward end, is a member 12 to which is hingedly or pivotally con-

nected, by means of bolts 13 or the like, the forward ends of the side beams 14 and 15.

To the rear end of the center beam a suitable ground working shovel 16 is connected. Like shovels, designated 17, are mounted adjacent the forward and rear ends of the side beams and these beams are provided with pairs of bolt holes 18 whereby, if desired, additional shovels may be mounted.

Handles 19 are connected at their forward ends to the center or main beam as at 19^a and are braced intermediate their ends by means of stays or braces 20. These braces 20 are connected to the respective handles 19 and to the beam 10. Further, the side beams are connected to the handles and the handles additionally braced by means of relatively long braces 21.

Mounted on the center beam 10 for movement longitudinally thereof is an adjustable slide 22. The slide is of one piece and is preferably formed of sheet metal, folded into a U-shape. As shown the slide includes a top 23 arranged along the upper side of the beam, a bottom 24 arranged at the under side of the beam, and a connecting portion 25. The connecting portion is provided with a centrally located slot 26 to receive the beam 10.

Bolt holes 27 and 28 are formed in the top 23 and bottom 24 at opposite sides of the center thereof whereby bolts passing through said holes and connecting the top and bottom are at opposite sides of the beam. A hole 29 is provided in the top 23 for a purpose to be described.

After positioning part 12, slide 22 is placed on the beam 10 from rear end. Pairs of links 30 and 31 are pivotally connected with the slide at opposite sides of beam 10 by means of bolts or other fastening means 32 passed through the bolt holes 27 and 28. Sleeves or ferrules 33 are mounted on the bolts 32 and extend into holes 27 and 28 in the top and bottom of the slide and serve to maintain it in proper position both vertically and laterally of the beam 10 and thereby prevent binding. The remote ends of the links 30 and 31 are pivotally connected to the side beams 14 and 15 respectively.

It will be apparent that movement of the

slide 22 along beam 10 will result in movement of the side beams on their pivots 13 to swing said side beams in toward the center beam or outwardly therefrom. A pivoted operating lever 34 is provided for giving such movement to the slide. Lever 34 is connected to the slide by means of a link 35 having one end bent and passed through the lever (Fig. 6) and having its other end curved and passed through the opening or hole 29 in the slide (Figs. 2 and 3).

The lever 34 carries a spring pressed locking bolt 36 for cooperation with a toothed segment 37 to maintain the lever in the desired position. This bolt is slidably mounted in a U-shaped clip 38 carried by the lever 34 and is normally urged downwardly into engagement with the segment by means of a coil spring 39. A pivoted hand piece 40 is adapted for manipulation to withdraw the bolt from engagement with the segment, by means of connecting rod 41, to permit movement of slide 22.

When the bolt 36 is withdrawn from engagement with the toothed segment, the lever 34 may be swung rearwardly to impart a similar movement to the slide. This (assuming the parts to be in the position shown in Fig. 1) will result in the links 30 and 31 being moved to form a straight line, relatively, and accordingly the side beams will be moved away from the main beam so that a wider path will be cultivated. The bolt locks the parts in their new position.

Since the slide 22 is formed from a single sheet of stock, suitably punched and folded or bent it lends itself to quantity production. Also, being a single unitary element it is impossible for it to get out of order. In addition, by a comparison of Figs. 2 and 3 the action of the curved end 42 of link 35 will be made clear. During rearward movement of the slide 22 the hooked end 42 contacts with the wall of the opening 29 only. However, on the forward movement of the slide the end contacts with a wall of the opening 29 and further contacts with the bottom wall 24 of the slide as at 43. From this it will be readily seen that the simplified connection between lever 34 and slide 22 provides for complete control of the slide by the lever.

Having thus described the invention what is claimed is:—

1. In a cultivator having a main beam and side beams hingedly connected thereto, an adjustable slide on the main beam, links pivotally connected at their ends to said slide and side beams respectively, an operating lever for moving the slide along the main beam, and a connecting link between said lever and said slide, one end of the link being curved and fitted into an opening in the slide, said curve being such that on the rearward movement of the slide the curved end contacts only with one edge of the opening and on the for-

ward movement of the slide the curved end contacts with another edge of the opening and with the bottom portion of the slide.

2. In a cultivator having a main beam, a slide on said beam, said slide comprising a single sheet of material of general U-shape having an opening in its connecting portion to receive the main beam, said slide being disposed in a longitudinal position of the beam and forming top and bottom portions and having bolt holes in said top and bottom portions, bolts positioned in said holes and connecting the top and bottom of said slide and arranged at each side of said beam, sleeves on said bolts between the top and bottom of the slide to hold said top and bottom against displacement, and operating arms attached to the end portions of the said bolts.

Signed at Bridgeport, in the county of Fairfield and State of Connecticut, this 7th day of May, A. D. 1927.

ARTHUR W. REYNOLDS.
